UNITED STATES PATENT OFFICE

2,526,166

GREASE COLLECTOR

Carlos W. Smith, Springfield, Oreg.

Application December 24, 1947, Serial No. 793,606

4 Claims. (Cl. 98—115)

1

This invention relates to new and useful improvements in grease collectors and the primary object of the present invention is to provide an attachment for the air ventilating pipe of a grill, so designed as to receive the normal drippings of grease that fall from such an air ventilating pipe.

Another important object of the present invention is to provide a grease collector for the air ventilator pipes of grills which will function as a baffle to distribute the air that is normally drawn or sucked into the pipe by an exhaust fan.

A further object of the present invention is to provide a grease collector for the air ventilating pipe of a grill that is small and compact in structure, and which may be quickly and readily applied to and removed from position relative to the ventilating pipe for convenient cleaning or the like.

A still further aim of the present invention is to provide a grease collector that is simple and practical in construction, strong and reliable in use, neat and attractive in appearance, relatively inexpensive to manufacture, and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is an elevational view of a conventional grill including an air ventilating pipe and hood (shown in section), and showing the present invention applied relative thereto, and with parts of the present invention broken away;

Figure 2 is a top plan view of the present grease collector; and

Figure 3 is an enlarged longitudinal vertical sectional view of the grease collector taken substantially on the plane of section line 3—3 of Figure 2.

Referring now to the drawings in detail, where-in for the purpose of illustration, there is disclosed a preferred embodiment of the present invention, the numeral 10 represents an air ventilating pipe that is disposed over a conventional grill 12, which is provided with a suction fan (not shown) for drawing off the fumes or smoke leaving the grill from articles being cooked on the grill. Rigidly secured within the lower end 14 of the pipe 10, is the central annular flanged portion 16 of a hood or shield 18 having inclined walls 20 and a central opening 22 that communicates with the pipe 10 and which is spaced above the grill 12.

2

The numeral 24 represents the present grease collector generally, comprising a preferably hollow, conical body 26 having an open lower end 28. Circumferentially spaced about the lower end of the body 26, and rigidly secured to the outer periphery of the body 26 are the outwardly turned end portions 30 of a plurality of upstanding support straps or arms 32, the longitudinal axes of which are spaced parallel to the longitudinal axis of the body 26. The upper ends of these arms 32 are turned outwardly to provide hook portions 34 that frictionally engage the upper edge 36 of the annular flange portion 16 to suspend or hang the body 26 in spaced relationship to the body 10 and within the shield 18.

Rigidly secured to the lower end 28 of the body 26, is an annular base or retaining plate 38 of a diameter greater than the open end of the body and also the opening 22 of the shield 18. This plate 38 is provided with an upstanding annular flange portion 40 that is spaced relative to the outer periphery of the body 26, to define an annular chamber or channel 42.

In practical use of the device, grease falling from the pipe 10 will engage the outer periphery of the body 26 and will be conducted to the channel 42. It should be noted, that the body 26 is spaced relative to the lower end 14 of the pipe 10, so that the plate 38 will function as a baffle to distribute the suction or air effected by the fan mounted in the pipe 10 over a larger area than is normally prevalent without the use of such a grease collector.

In view of the foregoing description taken in conjunction with the accompanying drawings it is believed that a clear understanding of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claims.

Having described the invention, what is claimed as new is:

1. A grease collector comprising a hollow conical body having an open major end, a grease collecting trough embracing the major end of said body and including a bottom wall closing the major end of said body, and a plurality of hanger arms attached to and rising from said body and having terminal hooks.

2. A grease collector comprising a conical body, a base plate carried by the major end of said

body and having an upstanding flange embracing said body and spaced outwardly from the outer periphery of said body to define an annular grease collecting channel, and means for suspending said body in a substantially vertical position below the inlet of an exhaust, said means including a plurality of hanger arms carried by said body and having terminal hooks.

3. In a grill shield having an outlet conduit and an air ventilating pipe having one end embracing the outlet conduit; a grease collector comprising a vertically disposed conical body having a downwardly and outwardly inclined outer surface, a plate carried by the base of said body and having an upstanding continuous flange spaced about the outer surface of said body to define a collection channel to receive grease on the outer surface of said body, a plurality of upstanding arms carried by the body, and hooks at the free ends of said arms for engaging the 20 outlet conduit.

4. The combination of claim 3, wherein said conduit and said body are co-axial.

CARLOS W. SMITH.
